[57] **CLAIM**

The ornamental design for player/recorder for speech cards, as shown and described.

DESCRIPTION

FIG. 1 is a top, front and left side perspective view of a player/recorder for speech cards showing my new design; and

FIG. 2 is a top and rear perspective view thereof. The right side of the player/recorder is a mirror image of the left side except for the omission of the plug element. The bottom is plain and unornamented.
